UNITED STATES PATENT OFFICE

2,370,676

PIPE

David Chester McCutcheon, Brooklyn, N. Y.

Application April 21, 1941, Serial No. 389,486

2 Claims. (Cl. 131—181)

This invention relates to improvements in pipes.

This invention relates to smoking pipes and cartridges therefor. It has for its objects:

First, to provide a new and improved pipe for use with cartridges of tobacco.

Second, to provide such a pipe which may be easily loaded in this manner and in which a slight cake will not interfere with insertion of the tobacco.

Third, to provide such a pipe and a cooperating tobacco cartridge made especially therefor.

Fourth, to provide a new and improved tobacco cartridge for pipes.

Fifth, to provide such a cartridge which seals in the tobacco and keeps it moist and confined and which may be easily removed and be disposed of after the pipe is filled.

Other objects and advantages pertaining to details and economies of construction and operation will appear from the description to follow. The invention is defined in the claims. A preferred embodiment of my invention is illustrated in the accompanying drawing, in which:

Fig. 1 is a perspective view of my improved pipe.

Fig. 2 is a view partly in section of my pipe and cartridge showing how the parts cooperate in filling the pipe.

Fig. 3 is a sectional view on line 3—3 of Fig. 5 of my improved cartridge in filled condition.

Fig. 4 is a sectional view thereof, showing how the plunger-like closure operates.

Fig. 5 is a bottom view of the cartridge.

My improved pipe 1 is standard in most particulars, having a bowl 2 with an opening 3, and a stem 4. Projecting inwardly from the inner wall of the bowl adjacent the opening thereof, but spaced from said opening is a thin rib 5 which forms a seat for a tobacco cartridge as shown in Fig. 2.

The cartridge 6 which fits into the opening of the bowl consists of a hollow body portion 7 which is of uniform cross section. One end is closed by a removable closure 8 which is fastened with a hinge 9 which may be of adhesive cellulose tape. This closure fits into the end of the body portion as shown and a portion of the periphery is cut away as shown at 10 for a purpose to be described.

Fitted in the other end of the body portion is a plunger-like disk 11 which fits against a shoulder 12 formed by bending in the body portion of the cartridge.

Fastened at 13 to the closure 11 is a flexible strip 14 of adhesive cellulose tape which is slightly fastened to the inside wall of the body portion 7.

This element is also turned out around the edge of the body portion as shown at 15 and fastened there. It extends through the opening formed at 10 by cutting away part of the closure 8.

5 The tobacco 16 is confined in the cartridge and is thus kept fresh and does not get out into the pocket of one carrying it.

In use, the cover 8 is removed. The body 7 is seated on the rib 5. The plunger-like closure 11 is then pressed as shown in Fig. 2, forcing the tobacco into the bowl of the pipe. As the closure 11 is pressed downwardly, the flexible element 14 is peeled from the wall of the body as shown in Figs. 2 and 4. The closure 11 may be pressed down to the rib 5 and when the body portion is removed, the flexible element removes the closure 11 because of the element 14 which connects them.

By providing the rib 5, I materially simplify the 10 filling of the pipe. The entering tobacco goes in easily since it is kept away from frictional contact with the walls of the pipe and with any slight cake which always forms in a pipe during smoking. With this arrangement, the formation of a 15 slight cake of less thickness than the radial dimension of the rib 5 does not interfere with the loading of the pipe. By constructing the rib 5 relatively thin and the diameter of the bowl cavity above the rib 5 less than the diameter beneath said rib 5 as shown in Fig. 2.

The terms and expressions which have been 20 herein employed are used as terms of description and not of limitation, and there is no intention, in the use of such terms and expressions of excluding any equivalents of the features shown and described. It is recognized that various modifications 25 are possible within the scope of the invention 30 claimed.

Having thus described my invention, what I claim as new and desire to secure by Letters Patent is:

1. In a structure of the class described, the 35 combination of a disposable tobacco cartridge comprising a hollow body portion of uniform cross section having a removable closure at one end and a plunger-like closure at the other end fitted in said body portion, and a flexible element 40 fastened to said plunger-like closure and extending along the inner surface of said body portion and fastened to said body portion adjacent said first mentioned end, and a smoking pipe having a bowl to fit said cartridge and having an inwardly 45 projecting thin rib adjacent but spaced from the

opening thereof on which said body portion is seated after its removable closure is removed, whereby the tobacco may be forced into the pipe without interference from a slight cake in said pipe of less radial dimension than said rib, the diameter of said plunger-like closure member being such that it may be forced inwardly beyond said rib and said body portion of said cartridge and said plunger-like closure by connection with said flexible element being removable as a unit after filling the pipe.

2. In a structure of the class described, the combination of a disposable tobacco cartridge comprising a hollow body portion of uniform cross section having a removable closure at one end and a plunger-like closure at the other end fitted in said body portion, and a flexible element fastened to said plunger-like closure and extend-

ing along the inner surface of said body portion and fastened to said body portion adjacent said first mentioned end, and a smoking pipe having a bowl to fit said cartridge and having inwardly projecting means adjacent but spaced from the opening thereof on which said body portion is seated after its removable closure is removed, whereby the tobacco may be forced into the pipe without interference from a slight cake in said pipe of less radial dimension than said inwardly projecting means, the diameter of said plunger-like closure member being such that it may be forced inwardly beyond said inwardly projecting means and said body portion of said cartridge and said plunger-like closure by connection with said flexible element being removable as a unit after filling the pipe.

DAVID CHESTER McCUTCHEON.
